UNITED STATES PATENT OFFICE.

FRED W. SAWYER, OF BOSTON, MASSACHUSETTS, ASSIGNOR TO THE UNION SWITCH AND SIGNAL COMPANY, OF SWISSVALE, PENNSYLVANIA, A CORPORATION OF PENNSYLVANIA.

BLOCK-SIGNAL SYSTEM FOR ELECTRIC RAILWAYS.

1,128,057.

Specification of Letters Patent.

Patented Feb. 9, 1915.

Application filed July 20, 1903. Serial No. 166,214.

To all whom it may concern:

Be it known that I, FRED W. SAWYER, of Boston, in the county of Suffolk and State of Massachusetts, have invented certain new and useful Improvements in Block-Signal Systems for Electric Railways, of which the following is a specification.

This invention relates to a block-signal system for electric railways employing direct car-operating currents and in which the electrical connection effected through the truck or other suitable part of the car controls the operation of the block-signals.

The primary object of the invention is to enable both car-rails to be employed for the return of the car-operating current supplied by the trolley-wire or power-rail and to allow the two rail-lines to be cross-bonded if desired so as to maintain a like potential in each rail.

In the preferred form, herein illustrated, for carrying the invention into effect, the two rail-lines are each composed of sections forming blocks and the several sections of each rail or rail-line are bonded together by impedances which afford a free passage to the direct car-operating current but impose a reactance or inductance in the path of the alternating current or currents employed to control the block-signals. Suitable signaling-units, which may take various forms, are associated with the several signaling-blocks and supplied with alternating currents, the alternating circuits being completed as regards signal-operative current by the passage of a car into the block and acting through suitable connections to control the signal and set it in the danger-position. Other impedances are or may be employed to cross-bond the rail-sections of each block and maintain the two rails at an even potential for the direct current, said impedances, however, reacting against the operating passage of alternating current from one rail to the other in a manner to set the signals.

Of the accompanying drawings,—Figure 1 represents a diagrammatic view of an electric-railway signaling system embodying this invention. Fig. 2 represents a view showing a modification of the system. Fig. 3 represents a power-operated element for substitution in said modification.

The same reference characters indicate the same parts in all the figures. 55

Referring to Fig. 1, 10 10 indicates the two rails or rail-lines forming the car-track, and each rail divided into sections whose pairs form a series of signaling-blocks 12 13 14. At the joints between adjacent blocks, the rail-ends may be separated by insulation 15 but the sections are not electrically isolated, as will appear. The pair of wheels and axle 16 symbolize a car running on the rails and adapted to effect an electrical connection between them.

17 17 are impedances bonding the adjacent sections of each rail 10 and so constructed as to be of low ohmic resistance but capable of imposing a reactance in the path 70 of the alternating currents supplied to the blocks so as to prevent the passage from one block to another of an alternating current in such a condition as to effect the operation of the signal. Similar impedances 18 are 75 inserted as cross-bonds between the pairs of rail-sections of the several blocks, said impedances being constructed to freely pass the direct current and thus maintain an even potential in the two rails, but reacting 80 against the passage of an alternating current capable of operating the signaling-units.

19 represents the trolley-wire or power-rail for supplying direct current to the cars, 85 and 20 represents the direct-current generator-set connected to said wire or rail and to the track-rails 10 10.

The signaling-unit located at the desired signaling-point in each block includes in 90 this embodiment a motor-generator set 21 comprising a direct-current motor 22 connected in circuit between the wire 19 and rails 10, and an alternating-current generator 23 having its shaft coupled to that of 95 the motor. The circuit-wires 24 25 of this alternator are connected to the respective rail-sections 26 26 of the block 13 and in the circuit of the generator is interposed a protective element 27 which may be either 100 an impedance or a resistance. A rotary converter is of course a well-known substitute for the motor-generator and is an equivalent in this connection. Both of these devices and their equivalents I include under 105 the term "mechanical power-operated de-

vice," meaning a device having movable mechanism influenced by the variation in power-function of the alternating signal-block current and influencing the direct current which controls the signal. The circuit of the motor 22 contains a relay 28 controlling a local circuit 29 for operating the signal-device 30.

In the operation of the above-described device, it is evident that when the car 16 is in the block 12 or any block antecedent to the block 13, the alternating current supplied by the continuously-propelled alternator 23 will find a complete circuit through the alternator, the car-rails 10 and the car 16, but will have its power-function altered by having to pass through one or more pairs of impedances 17. The alternating current passed by these impedances and also by the impedance 18 in that block is a lagging and largely a wattless or non-power-consuming current and therefore the effort required of the motor 22 to drive the alternator 23 is relatively small. Hence the circuit of the motor 22 will not pass enough current to operate the relay 28 and close the circuit of the signal 30. After the car 16 has passed the impedances 17 and entered the block 13, it short-circuits the impedance 18 and directly completes the circuit of the alternator 23. The current supplied by said alternator will then be in phase or nearly so, and hence a power-consuming current. More effort is required of the motor 22 to drive the alternator 23 and more current passes through the circuit of said motor and through the relay 28. Said relay will be operated by this increase of current and will set the signal 30 in the danger-position. As soon as the car passes out of the block 13 into the block 14 the impedances 17 connecting said blocks 13 14 become interposed between the car and the block 13 and the signal 30 resumes its safety-position.

In the modification shown in Fig. 2, an alternator 31 common to the several blocks, supplies through transformers 32, alternating current to the alternating circuits 33 of the several blocks, there being, as will be well understood, a transformer for every block. In the circuit 33 is interposed a solenoid 34 for operating the signal 30 and which may, as shown, be shunted by condensance 35 to counteract the current-lag imposed by the solenoid. Said solenoid is a current-operated device as distinguished from a power-operated device, that is, its operation depends upon variations in the current flowing in the circuit 33 (and not upon variations in the power supplied by said circuit). Such an installation would require a more expensive construction of the impedances 17', which I have shown connecting the rail-sections of adjacent blocks in this view, and for this reason the form of the invention

shown in Fig. 1 is preferred, although I regard Fig. 2 as a practicable construction.

It will be apparent that instead of the current-consuming solenoid 34 in Fig. 2, I may substitute any suitable power-operated device for controlling the signal 30, such for example as the device shown in Fig. 3, in which a field 36 varies the torque on a spring-held armature 37 controlling a local circuit 38. In such a case the expensive construction of the impedances 17' above alluded to is avoided.

Referring to Fig. 3, 40 is a resistance in series with the winding 39 of the magnet 36 and acting to restrict the delay of phase of current through the coil 39. 41 is a winding on stationary core 42, said winding being connected in parallel with the branch including coil 39 and resistance 40. As shown, the fields due to these two windings are at right angles to one another and differ in time as indicated. The spring-held armature 37 is any suitable induced element, such as a cylinder of copper or aluminum. 43 is a contact arm arranged on the armature 37, which is rotated against the tension of the spring 45 to make contact with the terminals 44 of the local circuits 38. This induction relay device consumes a comparatively small quantity of energy, thus avoiding an expensive construction of the impedance 17', as stated.

It will occur to those conversant with the art that the principles of this invention extend to electric-traction systems employing two conduit-wires or two over-head wires, one of which acts as a return for the other, in which case the arms of the shoe or double trolley would be connected by a device such as a condenser for passing the alternating current but not the direct current. As I do not, however, consider this application of the invention a particularly useful one in the present state of the art, I have not made special illustration of it.

I claim:

1. The combination with a railway system comprising traffic rails and an electric power circuit of which the rails form one side; of signal block circuits formed by insulations at intervals in each rail; a source of alternating current for each signal block circuit; impedances shunting the insulations in said rails and acting to give electrical continuity to both rails as conductors for the power current while restricting the difference of potential due to the sources of signal current to their respective blocks, and impedances connected as cross-bonds, equalizing differences of potential due to power circuit but maintaining differences of potential due to the sources of signal current.

2. The combination with a railway system comprising traffic rails and an electric power circuit of which the rails form one

side; means for dividing the rails into sections so that they may form part of track circuits; a source of alternating current for each track circuit; a signal circuit for each 5 track circuit; and means for controlling said signal circuits by changes in power factor of the current furnished to its track circuits.

3. The combination with a railway system 10 comprising traffic rails and an electric power circuit of which the rails form one side; means for dividing the rails into sections so that they may form parts of track circuits; a source of alternating current for each 15 track circuit; a signal circuit for each track circuit; a relay device controlling said signal circuit and connected across the power circuit; and means whereby said relay is responsive to variations of a characteristic of 20 the track circuit current.

4. The combination with a railway system comprising traffic rails and an electric power circuit of which the rails form one side; block sections formed by rail insulations; impedances shunting said insulations; a signal circuit for each block section; signal circuit controlling means located in a primary circuit; and a source of track circuit current secondary with respect 25 to said primary circuit.

5. In a signal system; signals; signal circuits for said signals; a source of alternating current corresponding to each signal and connected between the track rails corresponding to said signal; and means controlling said signal circuits in response to changes in the power factor of the alternating currents in the track rails.

6. In a signal system; block signals guarding successive portions of track; signal circuits for said signals; a source of alternating current connected between the rails of the portion of track guarded by each signal; and a relay device for each source including 45 a rotor and a stator having a plurality of

energizing coils carrying currents of different phase, each relay device controlling the corresponding signal circuit.

7. In a signal system; traffic rails divided by insulation to form block sections; a source of alternating current for each such section connected between the rails thereof; a signal circuit for each block section; and an induction motor relay device having a 50 rotor and a plurality of stator energizing 55 circuits controlling each signal circuit.

8. In a signal system; traffic rails divided by insulation to form block sections; a source of alternating current for each such section connected between the rails thereof; a signal 60 circuit for each block section; and an induction motor relay device having a rotor and a plurality of stator energizing circuits controlling each signal circuit and operated by the current from the corresponding 65 source of signal current.

9. A relay for alternating current signal system comprising an armature acting in response to magnetizing impulses displaced in phase and in position; a stationary field 70 magnet system producing said impulses and energized by a plurality of energizing coils; and means for producing currents of different phase in said coils.

10. In a signal system; block signals 75 guarding successive portions of the track; signal circuits for said signals; a source of alternating current connected between the rails of the track guarded by each signal; and a relay device for each source including 80 a rotor, a stator, and a plurality of energizing coils carrying currents of different phase, each relay device controlling the corresponding signal circuit.

In testimony whereof I have affixed my 85 signature, in presence of two witnesses.
